UNITED STATES PATENT OFFICE.

ADOLPH W. HOLL, OF CLEVELAND, OHIO.

CLAY AND SAND SCREEN.

977,009.

Specification of Letters Patent. Patented Nov. 29, 1910.

Application filed August 2, 1909. Serial No. 510,928.

To all whom it may concern:

Be it known that I, ADOLPH W. HOLL, a citizen of the United States, residing at Cleveland, in the county of Cuyahoga and 5 State of Ohio, have invented new and useful Improvements in Clay and Sand Screens, of which the following is a specification.

My improvement relates to improvements in the form of the screen bars with means 10 for their support and the means for keeping clear, the openings between said screen bars.

I attain these objects by the mechanism illustrated in the accompanying drawing, in which—

15 Figure 1 is a top view showing part of the screen bars and clearing blades in position. Fig. 2 is an elevation of the right side. Fig. 3 is a longitudinal sectional view. Fig. 4 is a cross section of a side frame showing 20 connecting bars and guides. Fig. 5 is a cross section of screen bar clamp. Fig. 6 is section of center support for screen bars. Fig. 7 is an enlarged section of screen bars, supporting and spacing comb and clearing 25 blades.

Similar figures refer to similar parts throughout the several views.

The frame of the screen consists of spaced parallel channel-bars 30 and 31 between 30 which are secured end-bars 12 and which serve as supports for the ends of the screen-bars 10. Eye-bolts 32 are provided for the usual suspension of the screen. Said side or channel-bars 30 and 31 are mounted to 35 have the channels turned outwardly or in opposite relation, and carry therein the guides 34, whose functions will hereinafter appear. At the head of the screen frame the channel-bars 30 and 31 project beyond 40 the upper supporting or end-bar 12 and receive in suitable bearings the shaft 4. Said shaft 4 is rotated through the medium of drive-wheels 3 and carries preferably outside said bars 30 and 31, the cams 1 and 2.

45 Mounted in the guides 34, above mentioned, and capable of independent movement therein, are the connecting or shaking bars 14 and 16, whose relative positions are both seen in Fig. 4. It is evident 50 that the bars in channel iron 31 are arranged oppositely to those in channel iron 30, but are otherwise identical in arrangement and operation. A description of one side then will suffice for both. Bar 16 is comparatively larger than bar 14, and receives 55 the latter in a longitudinal recess, between

which and overhanging lips 34' on the guides 34 said bar 14 is slidably secured. The rear end of bar 16 is longitudinally slotted at 16' to inclose the shaft 4 and has its rear 60 end provided with a stud carrying the cam roller 26 which operates in the cam-groove of cam 1. The other bar 14, terminates at the rear side of the shaft 4 and is provided with a cam roller 28, which occurs oppositely to the roller 26. The cams 1 and 2 are formed to throw the rollers and consequently the bars 14 and 16 oppositely at the same instant, so that opposite reciprocations thereof may be effected, and the corresponding bars on side 31 are connected to the identical cam 2 in such relation that the movements correspond to the movements of the bars in side or bar 30. 70

Projecting from the bars 14 and 16 at 75 spaced intervals are the studs or lugs 22 and 24, which engage for sliding movement the slots 20' in crank arms 18 and 20. Said arms 18 and 20 are mounted on the shafts 5, 6, 7 and 8, said shafts being adapted to 80 carry the clearing blades hereinafter described. Said shafts are mounted between the bars 30 and 31 and project therethrough, to carry on their projecting ends the said crank arms 18 and 20. Thus, as bars 14 85 and 16 are reciprocated, the crank arms 18 and 20 are reciprocated through the medium of studs 22 and 24 to oscillate said shafts 5, 6, 7 and 8.

The clearing blades above mentioned, and 90 designated by 11 and 33, are hung on said shafts 5, 6, 7 and 8 in such relation that a blade will be provided for the space between each two screen bars, and each shaft carries its independent set. Said bars 14 and 16 95 being given independent reciprocating movements by the cams 1 and 2, the rocker-shafts and consequently the clearing-blades are given varying movements of oscillation. Thus the blades are forced between the screen-bars in sections or section by section, to the better manipulation of the sand or clay, and the prevention of the clogging usual to ordinary screens as the clay is fed from top to bottom thereof. 100

Whenever the nature of the clay or sand is such as to need but one set of clearing blades, all but one of the cam rolls may be removed, or one from each cam, thus giving alternate sections of the screen the service of 110 clearing bars, or by means of a locking screw 39 which is threaded in bars 14 and may be

used with one of the cam rolls removed, both connecting bars on that side may be driven in unison.

Should it be desired to operate all blades in unison the cams may be set to work in unison with one roll in each, and the locking screw in each side in position as described, thus giving all blades the same action at the same time. It will be seen that the clearing 5 blades are in the form of elbows, thus keeping their shafts below and out of the way at the same time having the effect of bringing the blade into action for its whole length 10 at nearly the same time. The upper corner of the clearing blade is extended so that it never quite leaves the opening in which it works, so that any injury to the screen bars shall not prevent the movement of the blades or cause them to enter wrong spaces, or to 15 lift, or to interfere with the screen bars.

I call special attention to the cross section of my screen bars which I make in the form of sectors, thus giving me the rounded upper edge with its advantages as found in the 20 use of wire, and at the same time my wide bars with diminishing thickness allows any material entering the opening to pass through besides giving me the necessary stock for 25 strength, and to allow my supporting and spacing combs to hold the bars firmly without obstructing the screen surface. By means of my screen bar clamp 36 I am able to release the ends of all the bars at once, to replace a damaged bar, or to put in a set of 30 combs having a different spacing, so that my screen may be quickly changed to any desired condition of spaces to meet varying 35 needs. Said clamp 36 consists of an L-shaped member 21' recessed to receive a beveled leaf or bar 36 below the projecting edge 40 of which the screen bars 10 are secured. Headed bolts 37, carrying nuts, are extended through said bar and said member 21' to permit the adjustment of the former. Thus 45 a ready change of the bars 10 in a new spacing thereof in combs 9 is permitted. Bolt 38 is a raising device to support the clamp bar 36 when the bars 10 are being adjusted.

When desired the bars may be in as many 50 pieces as conditions warrant by using my center support shown in Fig. 6 with the beveled ends of bars entered before the end

clamps are tightened, thus giving a smooth surface for any length regardless of the length of the bars.

Having thus described my invention, what I claim as new and desire to secure by Letters-Patent is—

1. In a screening device, in combination with the screening bars, a plurality of rock shafts, a set of oscillatory clearing blades mounted on said shaft, and adapted to enter between said bars, and sliding means operatively connected to said rock shafts to cause the latter to oscillate said blades between 65 said bars in successive order.

2. In a screening device, in combination with the screening bars, a plurality of transverse rock-shafts, clearing blades mounted on said rock-shafts to enter between said bars, 70 and slide-bars operatively connected to said rock-shafts to oscillate said blades.

3. In a screening device, in combination with the screening bars, a plurality of transverse rock-shafts, crank arms carried by said 75 rock-shafts, longitudinally movable slide-bars having slotted connections with said crank arms, means for reciprocating said slide-bars and clearing blades mounted on said rock shafts and adapted to be oscillated 80 between said screen bars.

4. In a screening device, in combination, with the screening bars, a plurality of oscillatory clearing blades adapted to enter between said bars, means for mounting said 85 blades, and means to rock said blades, said blades comprising elongated fingers having eccentrically formed heels apertured to be mounted on said mounting means and adapted to project a portion thereof continuously 90 between said screen-bars.

5. A screen, comprising, in combination, a frame having longitudinal channel-bars at its sides, slide-bars operative in said channel-bars, means to reciprocate said slide-bars, 95 transverse rock-shafts operatively connected to said slide-bars, longitudinal screen-bars and clearing blades mounted on said rock-shafts and adapted to be oscillated between said screen-bars.

ADOLPH W. HOLL.
